UNITED STATES PATENT OFFICE.

HANLEY M. DAVIS, OF CAMBRIDGE, MASSACHUSETTS.

WINDOW-CLEANING DEVICE.

Application filed May 29, 1925. Serial No. 33,722.

This invention relates to devices for cleaning windows and has as its principal object the provision of a simple and easily operated device adapted to be quickly and easily applied to a window sash, and adapted to clean the outside of the window pane effectively and rapidly while the operator manipulates the same from the inside of the window.

The foregoing and other objects and advantages of the invention will be better understood from the following detailed description taken in connection with the accompanying drawings, and the distinctive features of novelty will be thereafter pointed out in the appended claims.

Referring to the drawings—

Figure 1 is an elevation showing a portion of a window with the cleaning device of my invention applied; and

Fig. 2 is a transverse sectional view of the same.

S, S' indicate the upper and lower sashes, respectively, of an ordinary window structure. 10 indicates a housing or body member, preferably produced of stout sheet metal bent to a general U-shape in cross section, with one side thereof extended farther than the other and bent inward, as indicated at 11. The dimension of this housing is such that it is adapted to be fitted upon the top of the sash of an ordinary window with sufficient clearance for free movement. Within this housing, and adjacent the inner corners thereof, are mounted longitudinally-extending small rollers 12, 13 spaced inward from the wall of the housing sufficiently to permit a web or band 14 of stout flexible material, such as stout canvas or webbing, to be passed around said rollers within the housing with its end portions 14^a, 14^b extending downward from the housing at each side of the window when the device is in place.

The side 14^b of this band which extends outside the window sash is reinforced intermediate the length thereof, as indicated at 15, and preferably is provided with a series of eyelets 16, these typifying any suitable provision for detachably securing a swab 17, or like cleaning member, to the band. This swab is preferably secured detachably to the band by clips passing through the eyelets 16 of the reinforced portion of the band. Thus, by taking hold of the depending portions 14^a, 14^b of the band 14 and drawing them downward alternately, the swab 17 may be

caused to traverse the vertical extent of the window pane to be cleaned, the bent-in portion 11 of the housing serving to hold the adjacent portion of the band inward relatively close to the pane so that the swab is pressed firmly thereagainst.

In order to permit free and easy horizontal traverse of the housing 10 along the top of the sash so that the entire horizontal extent of the window may be reached by the swab, the housing 10 is provided with transversely-extending small rollers 18, 19 journalled therein adjacent its ends and inward of the rollers 12, 13.

The device thus constituted is adapted to be quickly and easily applied to the window sashes in operative position, and by its use the window panes, particularly the upper panes, may be quickly and effectively cleaned on the outer surfaces thereof without the operator having to reach out of the window at all, the two end portions 14^a, 14^b of the band extending for convenient actuation from a location within the window.

I am aware that the invention may be embodied in other specific forms without departing from the spirit or essential attributes thereof, and I therefore desire the present embodiment to be considered in all respects as illustrative and not restrictive, and refer to the appended claim rather than to the foregoing description to indicate the scope of the invention.

I claim—

A window-cleaning device comprising a housing substantially U-shaped in cross section and constructed and arranged to fit over the top of a window sash, the lower edge of the outer side of said housing being bent inward toward the window pane, transverse rollers mounted in said housing and adapted to engage the top of a window sash, longitudinal rollers mounted in said housing, a flexible band disposed within said housing, the horizontal portion thereof resting on said longitudinal rollers and vertical portions thereof depending inside and outside the window, respectively, the outside vertical portion passing under the window sash and terminating inside the window, and a swab detachably secured to the portion of said band depending outside the window.

In testimony whereof I have affixed my signature.

HANLEY M. DAVIS.
